Filed July 17, 1958, Ser. No. 749,275

4 Claims. (Cl. 313—77)

This invention relates to cathode-ray tube scanning apparatus, particularly useful in power systems in which it is desirable to maintain the power rating of the circuit at a relatively low value. Specifically, it relates to an auxiliary winding utilized to increase electron-beam deflection in one direction and which enables the use of deflection circuit components with lower power ratings.

In supplying scanning currents to the horizontal and vertical deflection yoke windings of a cathode-ray tube, it is sometimes found to be more difficult to secure sufficient power for producing deflection in one direction than for producing deflection in the other. This is particularly true in television receiver systems where approximately ten times as much power is required to produce horizontal deflection as compared to that necessary to produce vertical deflection. This increase in power is required due to increased losses occurring at the higher horizontal scanning frequencies. It is a serious problem even when vacuum tube deflection circuits are utilized. In the case of vacuum tube circuits the problem is overcome by using components with suitably high power ratings. However, in some applications such as transistor television receivers, it becomes important to provide some solution to this problem which will allow the use of circuit components which are smaller in size and therefore have lower power ratings.

An early solution is to be found in United States Patent 2,177,688, issued to Madison Cawein on October 31, 1939, wherein there is disclosed an arrangement of permanent magnets located around and abutting the neck of a television tube between the deflecting yoke and the tube bell for augmenting the horizontal deflection. However, such an arrangement is difficult to apply to cathode-ray tubes favored in present-day practice, especially those found in portable receivers, since the necks of such tubes are short and the available space around them is fully occupied by the yoke windings, the magnetic core around these windings, the ion trap, and perhaps the focusing and centering arrangements. Moreover, this magnetic core would tend to short-circuit the magnetic field of permanent magnets placed close to it. Furthermore, it is difficult to arrange permanent magnets in such a way as to prevent their field from producing a certain amount of undesirable picture distortion.

It is an object of the present invention to provide new and improved scanning apparatus to augment the electron-beam deflection and which avoids the disadvantages of prior such apparatus.

It is another object of the present invention to provide scanning apparatus which produces a constant magnetic field so distributed across the cross-section of the electron beam that substantially no distortion of the picture results.

It is a further object of the present invention to provide scanning apparatus which may be utilized in conjunction with small short-necked, wide deflection angle cathode-ray tubes without substantially increasing the size of such apparatus.

In accordance with the present invention, cathode-ray

2

tube scanning apparatus for providing augmented beam deflection comprises deflection winding means for scanning the beam, magnetic core means encompassing the deflection means, means for supplying a direct current and means including a four-pole auxiliary winding responsive to the direct-current supply means and disposed between the core means and the tube for providing a uniformly changing magnetic field across the beam-deflection area. In one form of the invention the auxiliary winding has its longitudinal sides distributed substantially sinusoidally about the tube. In another form, the sides are distributed uniformly through four angular regions about the tube.

For a better understanding of the present invention, together with other and further objects thereof, reference is had to the following description taken in connection with the accompanying drawings, and its scope will be pointed out in the appended claims.

Referring to the drawings:

Fig. 1 is a diagrammatic cross-sectional side view of a portion of a cathode-ray tube showing a preferred embodiment of the present invention;

Fig. 2 is a diagrammatic cross-sectional view through the neck of the cathode-ray tube of Fig. 1;

Fig. 3 shows components of magnetic intensity produced by the auxiliary winding;

Fig. 4 shows diagrammatically the manner in which the auxiliary winding is wound, and

Fig. 5 is a graph of magnetic potential over the inner surface of the auxiliary winding of Fig. 2 plotted against the angular distance around the circumference.

Referring to Figs. 1 and 2 there is shown cathode-ray tube scanning apparatus for providing augmented beam deflection which comprises in part deflection winding means for scanning the beam. This means includes horizontal and vertical deflection yoke windings 11, 11 and 12, 12 surrounding the neck of tube 10 and shown as concentrated windings for convenience. The deflection windings might alternatively be of the saddle-yoke construction described at pages 6-10 of Television Engineering Handbook, edited by Donald G. Fink, McGraw-Hill Book Co., Inc., 1957. These windings are preferably placed directly over the glass neck of the tube 10.

The cathode-ray tube scanning apparatus further comprises a magnetic core means encompassing the deflection means. As shown in Fig. 2 the magnetic core 13 surrounds the horizontal and vertical deflection windings 11, 11 and 12, 12 and auxiliary winding 15, in accordance with the present invention. The winding 15 is more fully described hereinafter. The core serves as a return path for the magnetic flux of all three windings.

In addition to the conventional deflection windings and the magnetic core, the apparatus further comprises means for supplying a direct current and means including a four-pole auxiliary winding responsive to the direct-current supply means and disposed between the core means and the tube for providing a uniformly changing magnetic field across the beam deflection area. In one form of the invention the auxiliary winding has its longitudinal sides distributed substantially sinusoidally about the tube.

In another form the auxiliary winding is symmetrical and has its longitudinal sides distributed uniformly through four angular regions being substantially equal to 60°. These means include in Figs. 1 and 2 the direct-current voltage supply 16 and the auxiliary winding 15, which is a single layer winding disposed between the magnetic core 13 and the horizontal and vertical deflection windings 11, 11 and 12, 12. The winding 15 has its longitudinal axis coaxial with the longitudinal axis 17 of cathode-ray tube 10. The coils of the winding 15, although they may be wound so as to lie substantially only in the flat portion of the deflection windings, are

preferably wound to conform to the configuration of the deflection windings. In winding the auxiliary winding the four coils comprising the winding are spirally wound in reverse sequence and serially connected so that the adjacent sides of any two neighboring coils produce a magnetic field in the same relative direction.

Referring to Fig. 4, the auxiliary winding is shown in developed form, namely, before being wrapped around the neck of the cathode-ray tube 10. The winding comprises four coils 18, 19, 20, and 21, each coil having the conductors in its longitudinal side preferably parallel and straight. For the case of sinusoidal distribution of the coil sides the densest portions of the windings are arranged at the horizontal and vertical axes relative to the desired direction of increased beam deflection. The direction of direct-current flow through the winding then determines the axis of increased beam deflection. For reasons to be explained hereinafter, it may be more practical to wind the coils without adhering to the rigorous sinusoidal distribution. In Fig. 4, one such preferred form of a winding is shown wherein each longitudinal coil side has a width which covers an angular distance of α thereby producing an angular distance of 2α when adjacent coils are placed in abutting relation. The angle, α , is preferably substantially equal to 30° . When wound in this fashion the magnetic pole, which is the center of the coil, has a width equal to the width of one longitudinal side of the coil.

In describing the operation of the apparatus, reference is made to Fig. 3 wherein the ideal magnetic field, developed by a sinusoidal distribution of coil sides of the auxiliary winding 15, is shown as having a vertical component intensity H_y directly proportional to the horizontal distance x from the longitudinal axis 17 of the tube 10 and reversing in direction with a reversal in x . In a television receiver in which it is desired to augment the horizontal deflection, the x axis would lie along the horizontal plane and would preferably orthogonally intersect the axis-of-rotation 17 of the tube 10. The linearly increasing magnetic field increases the horizontal deflection by a constant factor. While the vertical component H_y is produced there is unavoidably present, at the same time, the horizontal component intensity H_x which ideally is directly proportional to the vertical distance y from the axis. Such a field will then decrease the vertical deflection by a constant factor in the same manner in which the horizontal deflection was increased. Thus, less power is required of the horizontal deflection windings 11, 11 and correspondingly more power is required of the vertical deflection windings 12, 12.

Due to the ideal uniformly changing field developed, the picture is not distorted. By uniformly changing is meant linear variation with respect to distance from the tube axis. The reason for this lack of distortion can be shown as follows. Referring to Fig. 2, if the longitudinal axis of the auxiliary winding is large compared with its radius, in the field produced by this winding, the magnetic potential, V , must satisfy the equation:

$$0 = r^2 \frac{d^2 V}{dr^2} + r \frac{dV}{dr} + \frac{d^2 V}{d\theta^2} \quad (1)$$

where r and θ are the polar coordinates of any point within the field and distant from its ends. With a symmetrical four-pole field the solution of this equation becomes:

$$V = a_2 \frac{r^2}{R^2} \sin 2\theta + a_6 \frac{r^6}{R^6} \sin 6\theta + a_{10} \frac{r^{10}}{R^{10}} \sin 10\theta + \dots \quad (2)$$

where R is the inner radius of the auxiliary winding and the a 's are constants determined by the distribution and current of the auxiliary winding. As previously described, for the ideal condition of no distortion, the sides of the coils comprising the winding are substantially sinusoidally distributed about the neck of the tube. In 75

this case all the a 's of Equation 2 are at zero except a_2 , in which case the equation simplifies to:

$$V = a_2 \frac{r^2}{R^2} \sin 2\theta = 2a_2 \frac{r^2}{R^2} \sin \theta \cos \theta \\ = 2a_2 \frac{xy}{R^2} \quad (3)$$

The magnetic intensity field then has the rectangular components:

$$H_x = -\frac{dV}{dx} = -2a_2 \frac{y}{R^2} \quad (4) \\ H_y = -\frac{dV}{dy} = -2a_2 \frac{x}{R^2}$$

Thus H_x is independent of x and directly proportional to y . H_y is independent of y and directly proportional to x . These are the desired relations illustrated in Fig. 3. The corresponding additional deflections d_h and d_v are indicated by the dotted arrows, the current of the auxiliary winding having such direction as to increase horizontal deflections at the expense of decreased vertical deflections.

In place of a sinusoidal distribution, it may be more convenient to use an auxiliary symmetrical winding uniformly distributed over portions of the circumference, as illustrated in Fig. 2. The magnetic potential just inside the auxiliary winding ($r=R$) is then as represented in Fig. 5 and as expressed by the Fourier series:

$$V = k \left(\sin 2\alpha \sin 2\theta + \frac{1}{3^2} \sin 6\alpha \sin 6\theta + \frac{1}{5^2} \sin 10\alpha \sin 10\theta + \dots \right) \quad (5)$$

where 2α is the angle subtended by each uniformly distributed belt of conductors and k is a constant proportional to the current and the number of turns.

If 2α is chosen to be 60° , then

$$\sin 6\alpha = \sin 60^\circ = 0 \quad (n=1, 3, 5, \dots) \quad (6)$$

Equation 5 then reduces to

$$V = k \sin 60^\circ \left(\sin 2\theta - \frac{1}{5^2} \sin 10\theta + \frac{1}{7^2} \sin 14\theta - \frac{1}{11^2} \sin 22\theta + \dots \right) \quad (7)$$

At any point r, θ in the field, the magnetic potential, by Equation 2, is then

$$V = k \sin 60^\circ \left(\frac{r^2}{R^2} \sin 2\theta - \frac{1}{5^2} \frac{r^{10}}{R^{10}} \sin 10\theta + \frac{1}{7^2} \frac{r^{14}}{R^{14}} \sin 14\theta - \dots \right) \quad (8)$$

To obtain an estimate of the distortion due to the departure of this magnetic potential from the ideal sinusoidal distribution, the radial and tangential components of magnetic intensity may be found from Equation 8:

$$H_r = -\frac{dV}{dr} = -k \sin 60^\circ \left(\frac{2r}{R^2} \sin 2\theta - \frac{1}{5} \frac{r^8}{R^8} \sin 10\theta + \frac{1}{7} \frac{r^{12}}{R^{12}} \sin 14\theta - \dots \right) \quad (9)$$

$$H_\theta = -\frac{1}{r} \frac{dV}{d\theta} = -k \sin 60^\circ \left(\frac{2r}{R^2} \cos 2\theta - \frac{1}{5} \frac{r^8}{R^8} \cos 10\theta + \frac{1}{7} \frac{r^{12}}{R^{12}} \cos 14\theta - \dots \right) \quad (9)$$

Using the maximum values 1 of the sines and cosines, the values of the second terms relative to the first are each equal to

$$\frac{1}{5} \frac{r^8}{R^8} = \frac{1}{5 \cdot 2^8} = \frac{1}{1280} \quad (10)$$

at a radial distance $r=R/2$ within which practically all of the electrons of the beam will be confined. This value, 1/1280, is so small that the departure from the ideal condition is unimportant; and the values for higher terms are smaller still. So distortion due to the departure of V in Fig. 5 from the ideal sinusoidal distribution is quite tolerable with $\alpha=30^\circ$.

When used in conjunction with a television-receiver scanning system the auxiliary winding need comprise merely a single layer. Since the voltage of this winding is low it requires no insulation other than the ordinary type of wire insulation.

It can be seen that the desired increase in beam deflection and a simultaneous decrease in component power rating may be produced by the present invention without occupying space about the tube already necessary for conventional image-reproducing apparatus. Since only a single layer, lightly insulated winding is necessary to practice this invention, the very small extra space required may be provided by slightly increasing the diameter of the magnetic core 13 or alternatively by decreasing the size of windings 11, 11 and 12, 12 or both.

While there has been described what is at present considered to be the preferred embodiment of this invention, it will be obvious to those skilled in the art that various changes and modifications may be made therein without departing from the invention, and it is, therefore, aimed to cover all such changes and modifications as fall within the true spirit and scope of the invention.

What is claimed is:

1. Cathode-ray tube scanning apparatus for providing augmented beam deflection, comprising: deflection winding means for scanning the beam; magnetic core means encompassing the deflection means; means for supplying a direct current; and means including a four-pole auxiliary winding responsive to the direct-current supply means and disposed between the core means and the tube for providing a uniformly changing magnetic field across the beam-deflection area, said auxiliary winding having its longitudinal sides distributed substantially sinusoidally about the tube.

2. Cathode-ray tube scanning apparatus for providing

augmented beam deflection, comprising: deflection winding means for scanning the beam; magnetic core means encompassing the deflection means; means for supplying a direct current; and means including a four-pole auxiliary winding responsive to the direct-current supply means and disposed between the core means and the deflection means for providing a uniformly changing magnetic field across the beam-deflection area, said auxiliary winding having its longitudinal sides distributed substantially sinusoidally about the tube.

3. Cathode-ray tube scanning apparatus for providing augmented beam deflection, comprising: deflection winding means for scanning the beam; magnetic core means encompassing the deflection means; means for supplying a direct current; and means including a four-pole symmetrical auxiliary winding responsive to the direct-current supply means and disposed between the core means and the tube for providing a uniformly changing magnetic field across the beam-deflection area, said auxiliary winding having its longitudinal sides distributed through four angular regions about the tube, said regions being substantially equal to 60° .

4. Cathode-ray tube scanning apparatus for providing augmented beam deflection, comprising: deflection winding means for scanning the beam; magnetic core means encompassing the deflection means; means for supplying a direct current; and means including a four-pole symmetrical auxiliary winding responsive to the direct-current supply means and disposed between the core means and the deflection means for providing a uniformly changing magnetic field across the beam-deflection area, said auxiliary winding having its longitudinal sides distributed through four angular regions about the tube, said regions being substantially equal to 60° .
